UNITED STATES PATENT OFFICE.

JAMES ARKELL, OF CANAJOHARIE, NEW YORK.

METHOD OF MAKING PAPER BAGS.

SPECIFICATION forming part of Letters Patent No. 325,148, dated August 25, 1885.

Application filed May 13, 1885. (No model.)

To all whom it may concern:

Be it known that I, JAMES ARKELL, of Canajoharie, in the county of Montgomery and State of New York, have invented a new and useful Method of Making Paper Bags; and I do hereby declare that the following is a full, clear, and exact description thereof, reference being had to the accompanying drawings, making part of this specification.

10 My invention relates to a method of making bellows-bottom paper bags of the kind having a bottom seam and one side seam only, and such as shown in another application filed by me September 13, 1884, No. 143,015.

15 In the accompanying drawings, forming part of this specification, Figure 1 is a plan view of a blank adapted to be folded up into a bag having a bellows bottom and one side seam only. Fig. 2 is a similar view of the blank after the 20 first folding operation toward making the bag. Fig. 3 is a plan view of the blank subsequent to the second folding operation. Fig. 4 is a like view after the third and last fold has been made. Fig. 5 is a perspective view of 25 the bag-bottom opened out, and looking at the interior thereof; and Fig. 6 is a plan view of the exterior surface of the bottom of the bag spread out as in condition for use.

In the several views the same letter of reference will be found to indicate the same part.

A, Fig. 1, is the blank, (of paper or other suitable material,) which is preferably creased along the lines 1, 2, and 3, to facilitate folding, as well understood, and which is supplied 35 with suitable adhesive matter along the narrow flap-like portion *c*, at the extremity of one of the longer sides of the sheet, and also along the edge or edge portion 5 of one of the shorter sides of the sheet, but on the opposite 40 side or face of the blank, as seen at Fig. 2. A portion of the stock of the blank is removed from the flap-like portion *c* from at about a point opposite the line 1 to the lower edge of the sheet, as shown, and the remaining triangular-like portion *c'* of flap *c* from line 1 to the bottom edge of the blank is preferably not supplied with paste or other adhesive matter.

To make a bag from a blank of the form shown at Fig. 1, and supplied with paste, as described, and preferably preliminarily creased 45 on the lines indicated, proceed as follows:

Fold on the line 1 the lower portion of the blank, and double it upon itself lengthwise of the sheet, and bring the blank into the condition illustrated at Fig. 2. Next fold on the 55 line 2 and bring the parts *a* *b* *a'* *b'* face to face, with the pasted portions on *a'* *b'* coinciding, and the blank will then be in the condition illustrated at Fig. 3. Then fold on the line 3 and turn over the pasted flap *c* down onto and 60 secure it to the portion *b*, as represented at Fig. 4. In making this last fold it will be understood, of course, that the triangular-like portion *c'* of the flap *c* is also turned over against *b*, and is confined between the latter 65 and the flap *c* when these parts shall have been pasted together. The finished bag (shown at Fig. 4) is now preferably, though not necessarily, creased obliquely along the dotted lines 70 4 4, to facilitate the opening of the bag into square-bottom form.

It will be seen from Figs. 4 and 5 that by folding and pasting a blank of the form shown at Fig. 1 (which is the best form now known to me) in the manner described a bag is produced with a "bellows-bottom," which may be opened or distended in square or rectangular form, and which has two seams, one at the middle of the bottom of the bag and the other at one side only thereof. A bag of such construction may be readily and cheaply made by machinery, as will be clearly understood by those skilled in the art to which my invention relates.

The blank may have its paste applied either 85 while in a perfectly-open condition, as at Fig. 1, or in a partially-folded condition, as at Fig. 2, and if done while in the last-named state the triangular-like portion *c'* may be conveniently pasted simultaneously with the side 90 flap, *c*; but, as before intimated, there is no actual necessity to paste this supplemental portion *c'*, as the pasted flap *c* overlaps it when folded down onto the part or side *b* of the bag.

Having now so fully described my invention that those skilled in the art to which it appertains may make bags of the kind referred to in a simpler and better way than heretofore, what I claim as new, and desire to secure by Letters Patent, is—

The hereinbefore-described method of making a bellows-bottom bag with one side seam

and one seam at the middle of the bottom, which consists in folding the blank shown on the line 1, thereby doubling it at its lower portion, in applying adhesive matter at the 5 localities *c* and *5*, in folding next on the line 2 and bringing the parts *a* *b* *a'* *b'* face to face, with the pasted portions on *a'* and *b'* coinciding, and then folding on the line 3 the pasted

flap *c* and securing it to the part *b*, all as shown and described.

In witness whereof I have hereunto set my hand this 4th day of May, 1885.

JAMES ARKELL.

In presence of—

P. D. VAN O'LINDEE,
WM. N. SMITH.
